N. PETERS, PHOTO-LITHOGRAPHER, WASHINGTON, D. C.

To all to whom these Letters Patent Shall come,

Whereas John Phillips and James Smallman citizens of the United States have alleged that they have invented a new and useful improvement in Steel Vessels, which improvement they state has not been known or used before this application was made; and that they do hereby believe that they are the true inventors or discoverers of this said improvement, have paid into the Treasury of the United States, the sum of thirty dollars delivered a receipt for the same and presented a petition to the Secretary of State, signifying a desire of obtaining an exclusive property in the said improvement and praying that a patent may be granted for that purpose. These and therefore to bear according to law, to the John Phillips and James Smallman their heirs administrators and executors for the term of fourteen years from the eighteenth day of September 1793, the full and exclusive Right and Liberty of making, constructing, using and vending to others to be used the said Improvement a description whereof is given in the words of the said John Phillips and James Smallman themselves, in the Schedule hereto annexed and made a part of these presents.

In Testimony whereof I have caused these Letters to be made out and the Seal of the United States to be affixed thereto.

Given under my hand at the City of Washington the eighteenth day of September in the year of our Lord one thousand eight hundred and eight years since the Declaration of the Independence of the United States of America the thirty fifth.

James Madison

By the President

R. Smith

Secretary of State

City of Washington, to wit.

I do hereby certify, that the foregoing Letters Patent were delivered to me on the eighteenth day of September in the year of our Lord one thousand eight hundred and ten, to be examined that I have examined the same & find them conformable to Law, & I do hereby cause the same to the Secretary of State within fifteen days from the date aforesaid, to go, on the eighteenth of September in the year aforesaid.

A. G. Rodney

(350.774.1)

Attorney General of the United States

The Schedule referred to in the Letters Patent & making part of the same, containing description in the words of the said John Phillips and James Smallman themselves of the

A wooden frame is constructed close aft on the Spar or Gun Deck, upon it is a perpendicular wheel with handles as in common use. The wheel moves on an axis on the deck which is a pinion, moving either in a vertical, horizontal, or spiral sector, fixed on the rear head (the draft is a vertical) this moves the under starboard & larboard.

The wheel has a catch to receive the pall, should the helmsman have occasion to leave his post, and the helm will keep steady.

The principle upon which the underpinning acts, is the same, as that described in the foregoing application, and therefore the inventors of this machine claim it to be included therein.
